CLAIM

The ornamental design for a mechanical controller, as shown and described.

DESCRIPTION

FIG. 1 is a top and front perspective view of a mechanical controller;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The evenly spaced broken lines in the drawings are included for the purpose of illustrating portions of the mechanical controller that form no part of the claimed design. The dash-dot broken lines located around the trigger portion in FIGS. 1-2 and 4-6 illustrate the boundary of the claimed design and form no part thereof. The trigger portion bounded by the boundary line in FIGS. 1-2 and 4-6 forms no part of the claimed design.
